UNITED STATES PATENT OFFICE.

ARTHUR O. HIGINBOTHAM, OF WORCESTER, MASSACHUSETTS, ASSIGNEE TO CHARLES B. FOSTER AND COMPANY, OF WORCESTER, MASSACHUSETTS, A COPARTNERSHIP CONSISTING OF CHARLES B. FOSTER, ARTHUR O. HIGINBOTHAM, AND JEROME R. GEORGE, ALL OF WORCESTER, MASSACHUSETTS.

STARTING DEVICE FOR INTERNAL-COMBUSTION ENGINES.

1,231,738.

Specification of Letters Patent.

Patented July 3, 1917.

Application filed May 2, 1914. Serial No. 835,846.

To all whom it may concern:

Be it known that I, ARTHUR O. HIGINBOTHAM, a citizen of the United States, residing at Worcester, in the county of Worcester and Commonwealth of Massachusetts, have invented a new and useful Improvement in a Starting Device for Internal-Combustion Engines, of which the following, together with the accompanying drawings, is a specification.

The present invention relates to starting devices for internal combustion engines utilizing compressed air for imparting movement to the pistons of such engines until the explosions begin to take place within the cylinders, and its object is to increase the efficiency of such starting devices, and to render the starting of the engine certain under any and all conditions.

In the application of compressed air starting devices to one, two and four cylinder engines, it is well known that when the piston or pistons of the engine are at the limits of their reciprocations, in other words on "dead-center", the admission of pressure medium to the cylinders imparts no movement to the pistons, and that therefore under such conditions all compressed air starters fail to operate. The present invention aims to overcome this difficulty by providing in conjunction with such a starter, and operatively connected thereto, means for imparting a slight initial rotation to the engine shaft in order to carry the piston or pistons off of dead-center, and I have illustrated one embodiment thereof in the accompanying drawings, in which—

Figure 1 is a diagrammatic representation of an internal combustion engine, having in my improved starting device applied thereto.

Fig. 2 is a section on line 2—2, Fig. 1.

Fig. 3 is a face view of a clutch mechanism forming a portion of my starting apparatus.

Fig. 4 is a section on line 4—4, Fig. 2.

Fig. 5 is a fragmentary view of a modified

form of control lever for operating the starting device shown in Fig. 1.

Like reference characters refer to similar parts in the different figures.

For the purposes of illustration I have shown diagrammatically a four cylinder engine 1, of the type ordinarily used on motor-vehicles, with a compressed air starting mechanism of any ordinary type applied thereto, said starting mechanism embodying a distributor 2, adapted to be supplied with air under pressure from a supply tank 3, and having pipes 4 leading therefrom to each cylinder of the engine, in the manner common to compressed air starters now in use. A suitable valve 5, provided in the pipe connecting the tank 3 and the distributor 2, controls the flow of compressed air to the distributor, said valve having a stem 6 projecting outwardly from its casing. In the present instance I have disclosed the engine 1 disposed below the operator's seat of a motor truck; a foot lever 8, in convenient reach of the operator, projects upwardly through the floor below the operator's seat, and is pivoted at its lower end to a fixed point on the framework of the vehicle. A spring 7 yieldingly holds said lever 8 in the position shown in Fig. 1. A bell crank lever 9, pivoted to the framework, has one arm pivotally connected to a link 10 pivoted to the foot lever 8, while its other arm extends below and engages the stem 6 of the control valve 5. When the lever 8 is pressed forward by the foot of the operator, the valve 5 is lifted off its seat, admitting air under pressure to the distributor 2, and to the proper cylinder of the engine 1 in the manner common to any of the ordinary types of compressed air starting devices.

The crank shaft 11 of the engine has keyed thereto, on its forward end, a sleeve 12. Said sleeve 12 has secured thereto, and preferably formed integral therewith, a cylindrical rim 13. In the embodiment of my invention shown in the drawings, the sleeve

12 is extended forwardly as shown at 14, forming a continuation of the crank shaft 11, in order to provide for the application of a starting crank, if desired. It will be understood, however, that in some cases the crank shaft 11 may extend forwardly sufficiently to project beyond the sleeve 12, in which case the extension 14 of the sleeve is unnecessary. Journaled on the sleeve 12 is 10 a second sleeve 15, which is provided with a number of radial arms 16, in the present instance four, lying within the annular space between the sleeve 12 and its rim 13. Each arm 16 is bored longitudinally to receive a 15 stem 17 projecting from the under side of a segmental bearing shoe 18. Each sleeve 18 is maintained in contact with the inner periphery of the rim 13 by a spiral spring 19, encircling the corresponding arm 16 and 20 bearing against the under side of the shoe and the sleeve 15, at its ends. The above described arrangement of parts constitutes a frictional clutching mechanism between the sleeve 12 and the sleeve 15.

25 The outer end of the sleeve 15 is reduced in diameter to form a shoulder 20 and has journaled thereon an arm 21, held against said shoulder 20 by a nut 22, carried on the extreme end of the sleeve. The portion of 30 the arm 21 which encircles sleeve 15 has an extension which provides an interior recess 23, interrupting the continuity of the bearing surface between the sleeve and the arm. A ball or roller 24 is disposed within said 35 recess, and lies in contact with the cylindrical surface of sleeve 15. The recess is enlarged at the upper end, so that when the shaft 11 rotates in the direction of the arrow A, Fig. 4, the rotation of sleeve 15 in 40 the same direction, through the medium of the frictional clutching mechanism, causes the ball 24 to be maintained in the enlarged upper portion of the recess, whereby an operative connection between the sleeve 15 45 and the arm 21 is prevented.

The outer end of arm 21 is pivotally connected to a substantially vertical link 25. The other end of said link 25 is pivotally connected to one arm of a bell crank 28, 50 pivoted to the framework, the other arm of said bell crank being pivotally connected to a link 29. The other end of link 29 has an elongated slot 30 which engages a pin 31 on the foot lever 8.

55 In the operation of the starting mechanism, the depression of the foot lever 8 admits compressed air to the proper cylinder of the engine as above described. If, however, the engine happens to be on dead-center, or for any 60 other reason fails to "turn over" under the influence of the pressure medium thus admitted, the further depression of the foot lever, whereby the pin 31 engages the for-

ward end of slot 30 and imparts a rocking motion to bell crank 28, causes a downward 65 movement of the end of arm 21, as shown by the arrow B, Fig. 4. The ball 24 is thereby squeezed between the wall of the recess 23 and the sleeve 15, causing the movement of the arm 21 to impart a slight 70 rotative movement to the sleeve 15, and through the medium of the frictional clutching mechanism, to the shaft 11. Such an initial rotation is sufficient to carry the pistons off dead-center and permits the 75 compressed air to operate in the usual way to carry the engine through a sufficient number of revolutions to effect its starting.

The springs 19 which hold the shoes 18 in frictional contact with the inner periphery 80 of rim 13 exert a comparatively light pressure on said shoes. Such a pressure produces sufficient friction to transmit to the shaft 11 the comparatively light force required to give it its initial movement, as 85 above described; but upon the occurrence of any strong or sudden force, such as would be occasioned by a back-kick of the engine, the shoes 18 slip within the rim 13 and hence there is no transmission of such a force to 90 the arm 21 and its connected mechanism. The slight force which might be transmitted to the arm 21 under such circumstances is prevented from reaching the foot lever 8 by a stop plate 27, mounted on the framework 95 against which the upright arm of bell crank 28 is adapted to strike, when it reaches the limit of its return movement.

In Fig. 5 I have illustrated a slightly modified form of construction in which the 100 pin and slot connection of the link 29 to the foot lever 8 is replaced by an ordinary pivotal connection 35. In the operation of the starting means so constructed, the initial mechanical movement of the engine shaft 105 through the agency of the clutch mechanism occurs simultaneously with the admission of the pressure medium to the cylinders, whereby at each operation of the starting device a slight movement of the shaft is insured 110 to assist the force of the air in overcoming any tendency of the pistons to stick, or to happen to be in such position.

I claim,

1. The combination with an internal combustion engine having a starting device, of a movable member for inaugurating the action of said starting device, and means, comprising a friction clutch having an operative connection with said member, for transmitting the movement of said member to the shaft of said engine. 115

2. The combination with an internal combustion engine having a starting device, of 120 a movable member for operating said start-

ing device, and means, brought into operation by the movement of said member beyond the position for operating the starting device, for imparting independent rotation 5 to the shaft of said engine.

3. The combination with an internal combustion engine having a starting device, of a movable member for operating said starting device, a second member having frictional engagement with the crank shaft of 10

said engine, and a clutching means between said members rendered operative by movement of said first member to operate said starting device.

Dated this 25th day of April 1914.

ARTHUR O. HIGINBOTHAM.
